Patented June 15, 1976

240,288

ROLLING PIN CUTTER

Jeffrey D. Wright, 1706 Gold SE.,
Albuquerque, N. Mex. 87106

Filed Sept. 13, 1974, Ser. No. 505,751

Term of patent 14 years

Int. Cl. D7—04

U.S. Cl. D7—43

FIG. 1

FIG. 2

FIG. 3

FIG. 4

FIG. 5

FIG. 1 is a front elevational view of a rolling pin cutter showing my new design.

FIG. 2 is an elevational view of the rolling pin cutter of FIG. 1 rotated 90°.

FIG. 3 is an elevational view of the rolling pin cutter of FIG. 1 rotated 180°.

FIG. 4 is an elevational view of the rolling pin cutter of FIG. 1 rotated 270°.

FIG. 5 is a developed plan view thereof of the roller portion.

I claim:

The ornamental design for a rolling pin cutter, as shown.
